UNITED STATES PATENT OFFICE.

JOHN L. LYNCH, OF STARBUCK, MINNESOTA.

EGG CRATE.

Application filed May 12, 1924. Serial No. 712,624.

To all whom it may concern:

Be it known that I, JOHN L. LYNCH, a citizen of the United States, residing at Starbuck, in the county of Pope and State 5 of Minnesota, have invented certain new and useful Improvements in Egg Crates, of which the following is a specification.

The present invention relates to an improved egg crate.

Difficulty is experienced in the manufacture of egg crates in securing a cover therefor which is inexpensive and which may be readily and securely fastened in place, but shall be easily removed when it is desired to 15 fill or unload the crate.

An object of the present invention is to make an egg crate with an improved type of cover fastening therefor.

Another object is to make an inexpensive 20 and durable interlocking fastening for an egg crate cover.

In order to attain these objects, there is provided in accordance with one feature of the invention, perforated lugs fastened to 25 a side of a crate, and a perforated spring fastened to an opposite side thereof. Projecting lugs are fastened to a cover for the crate to engage the perforated lugs, and a lug which may be slightly longer than those 30 which engage the perforated lugs is connected to the cover in a position to engage the perforated spring when the cover is in position on the crate.

These and other features of the invention 35 not specifically mentioned will be more fully brought out in the following description and the accompanying drawings, wherein similar reference characters are used to denote the same parts throughout the various views.

Referring to the drawings:

Figure 1, is a view in isometric projection 40 of an egg crate made in accordance with one form of the present invention.

Figure 2, is a view in front elevation of a 45 perforated spring member used to secure the cover in place.

Figure 3, is a view in front elevation of a 50 perforated lug and a portion of a crate.

Figure 4, is a view in elevation of a lug 55 connected to the top of a crate to engage a spring member connected to the body of the crate.

Figure 5, is a view in elevation of a lug 60 connected to the top of a crate to engage a perforated lug connected to the body of a 55 crate; and

Figure 6, is a view in isometric projection of a modified form of lug and lug engaging member with a portion of the crate body and top therefor, the portion of the crate body 60 being shown in dotted lines so as to permit the illustration of the lug connected thereto.

Referring to the drawings in detail, a 65 crate A may be built up of boards in a well known manner and lugs 1 are fastened to one side thereof as by means of screws. Each lug 1 is perforated at 2, the bottom of the perforation being preferably at a height from the top of the crate equal to the thickness of a cover to be used in conjunction 70 therewith. Also fastened to the body of the crate on the opposite side from the lugs 1 is fastened a spring member 3, the bottom of which is preferably at a height above the top of the top edge of the crate equal to the 75 thickness of a cover to be used therewith.

A crate cover B which may be built of 80 boards secured together by means of cleats 4 in a well known manner, has secured thereto at points to register with the perforations in lugs 1, metal members 5, a nose portion 6 of which extends over the edge of the cover in a manner to engage the perforations in the lugs 1 when the cover is in position. A third metal member 7 may be secured to the 85 cover by means of screws and this member is preferably provided with an elongated nose 8 having a perforation 9 therein. Spring member 3 is positioned to engage the nose 8 with the perforation therein. A pin 90 10 of a size to enter the perforation 9 in the nose of member 7 may be connected to the body of the box as by means of a chain and staple 11.

In placing a cover B in position, the noses 95 of metal members 5 are first introduced into the perforations in lugs 1, and the opposite side of the cover is then brought down so that the nose of metal member 7 engages the curved upper portion of spring member 3 100 moving it outward until the perforation therein registers with the nose of member 7, whereon the spring 3 snaps securely in engaging member 7, thereby locking the cover securely in place. To prevent displacement 105 of the spring 3 from contact with member 7 during transit, the pin 10 may be inserted in perforation 9 in metal member 7. To prevent lateral moving of the cover in the direction of spring member 3 to move 110 metal members 5 from engagement with the perforations in lugs 1, the cleats 4 may ex-

tend to within a short distance of the side of the crate to which is connected spring member 3.

The operation of the cover fastening illustrated in Figure 6 is similar to that shown in Figure 1, and will be apparent from the illustration and the foregoing description of the type shown in Figure 1.

What I claim is:

- 10 1. In an egg crate, a cover fastening, comprising perforated lugs connected to the body of an egg crate, a perforated spring connected to the opposite side of the body thereof, lugs to register with and engage 15 the perforated lugs connected to the body

of the crate and to removably lock a cover on an egg crate.

2. In an egg crate, a cover fastening, comprising indented members connected to the sides of the crate, projecting members interlockingingly engaging said lugs, a spring member connected to a side of the crate other than that to which the lugs are connected, a projecting member interlockingingly engaging said spring member upon seating the cover, and means connected interior of the cover to prevent lateral displacement thereof.

In testimony whereof I affix my signature.

JOHN L. LYNCH.
